UNITED STATES PATENT OFFICE.

WILLIAM E. KIDDER, OF KALAMAZOO, MICHIGAN.

FOLDING CHAIR.

Application filed July 13, 1925, Serial No. 43,241. Renewed February 6, 1929.

This invention relates to improvements in folding chairs.

The main object of this invention is to provide an improved folding chair which 5 may be formed of quite light material and at the same time one in which the parts are disposed so that they are not likely to be broken when in use or when collapsed.

Objects pertaining to details and economies of my invention will definitely appear 10 from the detailed description to follow.

I accomplish the objects of my invention by the devices and means described in the 15 following specification. The invention is clearly defined and pointed out in the claim.

A structure embodying the features of my invention is clearly illustrated in the accompanying drawing forming a part of this application, in which:

20 Fig. I is a front perspective view of my improved folding chair.

Fig. II is a perspective view of my improved chair partially folded.

Fig. III is a plan view of the folded chair.

25 Fig. IV is a side view of the folded chair.

Similar numerals of reference indicate similar parts in all of the views.

Referring to the drawing, the front legs 1, 1 and rear legs 2, 2 are pivotally connected 30 at 3' to be swung to crossed relation when erected or collapsed into the same plane with the front legs at the outer side of the rear legs. The front legs are substantially longer than the rear legs so that the upper ends 35 of the front legs project substantially above the plane of the upper ends of the rear legs. The rear legs are connected by the cross-rungs 3 and 4, the pivot 3' constituting a cross-rung.

40 The back side bars 5 are pivotally mounted on the outside of the upper ends of the front legs, the pivots 6 being substantially spaced from the lower ends of the back side bars. This permits these back side bars 45 being collapsed at the outer sides of the front legs 1, the legs and back bars being of the same width.

The back slats 7 are secured on the rear edges of the back side bars so that when the 50 chair is collapsed these back slats lie across and are supported by the collapsed legs. The back bars are connected at their lower ends by the cross rod 8 which engages in the notches 9 when the chair is erected, limiting the rearward movement of the back

and, through the seat to be described, supporting the rear legs in their open position. The seat bars 10 are pivotally mounted on this cross rod 8 and are pivoted at 11 to the upper ends of the rear legs. 60

The slats 12 of the seat are secured on the upper edges of these bars 10, the front slats 13 being of such length that they rest upon the legs when the chair is collapsed. This performs the double purpose of securing the 65 desired width to the seat and also the slats are effectively supported when the chair is collapsed so that heavy weights may be placed upon the collapsed chair without likelihood of breaking the back or seat slats, or 70 distorting the parts by putting undue stress upon the pivots.

My improved chair is very economical to produce, may be made of light material, and at the same time is strong and durable. 75

Having thus described my invention what I claim as new and desire to secure by Letters Patent is:

In a folding chair, the combination of 80 front and rear legs pivotally connected to be swung to crossed relation or to be collapsed into the same plane with the front legs lying at the outside of the rear legs, the front legs extending above the upper ends of the rear legs, a pair of back side 85 bars pivotally mounted on the outer sides of the upper ends of the rear legs to be collapsed forwardly at the outside of the front legs, the pivots being disposed in spaced relation to the lower ends of said side bars, 90 a cross rod connecting the lower ends of the back bars and coacting with the front legs limiting the rearward movement of the back, back slats secured on the rear edges of the 95 said back side bars so that the back bars may be collapsed forwardly into the plane of the legs with the back slats resting thereon and supported thereby, seat bars pivotally mounted on said back cross rod and on the upper ends of the rear legs, and seat slats 100 secured on the upper edges of said seat bars, the rear seat slats being of such length as to swing between the upper ends of the front legs and the front seat slats being of such length as to overlap and rest upon the collapsed legs to be supported thereby when the chair is collapsed. 105

In witness whereof I have hereunto set my hand.

WILLIAM E. KIDDER.
